SALT SHAKER

Raymond H. Ball, Scarsdale, N. Y.

Application February 21, 1935, Serial No. 7,606

2 Claims. (Cl. 65—45)

This invention relates to a shaker for granular material such as salt and the like.

The principal object of the invention is the provision of a shaker of the indicated character which protects the contents thereof from dust, moisture and atmosphere, so that the shaker will not become clogged due to the contents becoming compacted; which has means to stir the contents to cause it to discharge freely; which has means to prevent unintentional discharge of the contents; and which has means to seal the shaker by the mere act of placing it on a table or other suitable support.

The nature of the invention and its distinguishing features and advantages will appear when the following specification is read in connection with the accompanying drawing, in which:

Figure 1 is a central vertical section of a shaker embodying the features of the invention;

Figure 2 is a view similar to Figure 1 but showing the shaker inverted;

Figure 3 is a transverse section taken approximately on the line 3—3 of Figure 1; and

Figure 4 is a view of one of the parts of the valve structure.

Referring now more particularly to the several views of the drawing, it will be apparent that the shaker includes a reservoir or container 10 for the granular material, such as salt and the like. The container may be made of any suitable material, preferably glass, so that the contents thereof will be visible. The upper end of the container is closed and its lower end is open. A base 11 of metal or any other suitable material is applied to the lower end of the container, and in the present instance this is accomplished by internal threads 12 on the base for threading engagement with complementary threads on the lower end of the container 10. The base 11 has a central conical portion 13 which extends inwardly of the container, and said portion has a central dispensing or discharge opening 14 which is surrounded by a seat 15 embodied by the portion 13. By reason of the outward flare of the portion 13 the contents C of the container may be discharged through the opening 14 over a relatively wide area. The base 11 has a contact face 16 in a plane below the dispensing or discharge opening 14, on which the shaker rests when placed on a table or other suitable support, to effectively prevent dust, moisture, and air from entering the interior of the container 10 through the opening 14 when the shaker is not in use. The discharge opening 14 is controlled by valve body 17 having a conical portion 18 and

a conical portion 19 arranged reversely to the portion 18 to provide a seat contacting and material deflecting surface 20. Use is made of a hollow dome shape member 21 open at the lower end. The member 21 has a relatively large base portion 22 and small upper portion 23 integral with the portion 22. The base portion 22 has a laterally outwardly extending flange 24, and also has a plurality of holes 25 therein above the flange 24. The member 21 is held in place within the container 10 by the base 11 in the lower end of the container 10 between which the flange 24 is clamped. The conical portion 13 in relation to the member 21 provides a chamber 26 which is in communication with the interior of the container 10 by virtue of the holes 25, and said chamber 26 also will be in communication with the discharge opening 14 when the valve body 17 is off the seat 15. The chamber 26 surrounds and extends below the inner end of the discharge opening 14. The valve body 17 is freely arranged within the chamber 26 and its movements are limited by the upper portion 23 of the member 21. The valve body 17 is always caused to return to a position in which the face 20 thereof will engage the seat 15, when the face 16 of the shaker is brought to rest on a suitable support. In other words, the valve body 17 moves to a closing position in relation to the seat 15 under the action of gravity. Some of the contents of the container enters the chamber 26 through the holes 25 when the shaker is brought to rest. The upper end of the container is rounded as at 27 so that the shaker will be brought to rest on its base 11 when not in use.

From the foregoing it will be understood that the desired amount of the contents of the container may be discharged through the opening 14, and that this depends wholly on the amount of shaking motion given to the shaker. By imparting shaking movement of the shaker, the valve body 17 will be repeatedly unseated, thereby allowing some of the contents to be discharged through the opening 14 at the will of the user. While this shaking movement is imparted to the shaker, some of the contents of the container will be entering the lower end of the chamber 26, will pass upwardly therein, and will then be deflected downwardly by the face 20 of the valve body 17, through the opening 14.

It is to be observed that the member 21 constitutes means to prevent unintentional discharge of portions of the contents in consequence of the shaker being inverted out of curiosity. In this connection it is to be observed on reference to

Figure 2 that when the shaker is inverted some of the contents drops into the portion 23 below the portion 19, and the conical surface of said portion 19 deflects this trapped portion of the contents, away from the opening 14 into the lower end of the chamber 26, and thus prevents it from discharging through the opening 14 when the shaker is brought to rest right end up.

From the foregoing it will be obvious that portions of the contents of the container 10 may be discharged at will; that no leakage will result if the shaker is turned upside down or inverted and then returned to its proper position; that the only way contents may be discharged is by imparting a shaking motion to the shaker; and that the base 11 may be readily removed together with the member 21 and the valve body 17 so that container 10 may be replenished with granular material such as salt.

20 I claim:

1. A shaker for granular material including a container for the material open at the lower end, a removable part on said open end and having a discharge opening, a hollow dome shape part held in position by said first part and the open end of the container, said first part having an annular portion projecting into said dome shape part providing a chamber surrounding and below said discharge opening, a body freely movable within said dome shape part between it and said annular portion, said body having a conical portion, said dome shape part being apertured so that material may flow from the container

into the dome shape part to be deflected out of said opening by the undersurface of said conical portion, when up and down shaking motion is imparted to said shaker, the conical surface of said conical portion serving to deflect material away from said opening to keep it in said chamber, in the event that the shaker is inverted and then brought right end up.

2. A shaker for granular material including a container having a detachable base provided with a discharge opening surrounded by an annular inwardly projecting portion providing a seat, a hollow dome shape member held in position by said container and base, said dome shape member having a relatively small upper portion and a large base portion integral therewith, said inwardly projecting portion providing a chamber surrounding and below said discharge opening, and a body freely movable within said small upper portion of the dome shape member between it and said seat, said body having a conical portion, the base portion of the dome shape member being apertured so that material may flow from the container into the dome shape part, to be deflected out of said opening by the undersurface of said conical portion, when up and down shaking motion is imparted to the shaker, the conical surface of said conical portion serving to deflect material away from said opening to keep it in said chamber in the event that the shaker is inverted and then brought right end up.
